UNITED STATES PATENT OFFICE.

WILLIAM H. PEIRCE AND ELIAS A. C. SMITH, OF BALTIMORE, MARYLAND.

METHOD OF AND CONVERTER VESSEL FOR BESSEMERIZING COPPER MATTE.

942,346.

Specification of Letters Patent. Patented Dec. 7, 1909.

Application filed June 13, 1908. Serial No. 438,286.

To all whom it may concern:

Be it known that we, WILLIAM H. PEIRCE and ELIAS A. C. SMITH, citizens of the United States, and residents of the city of Baltimore, State of Maryland, have invented certain new and useful Improvements in Method of and Converter Vessels for Bessemerizing Copper Matte, of which the following is hereby declared to be a full and exact description, reference being had to the accompanying drawings, which form part of this specification.

In customary method, the bessemerizing of copper matte to obtain blister copper, involves the use of an air blast projected through the molten matte as it lies charged within a suitable converter vessel having a quartzose or other highly silicious lining. The air promptly reacts with the hot iron sulfid, present as a necessary constituent of the matte, driving off the sulfur in gaseous form (SO_2) while the iron burns to an oxid, and, at the high temperature prevailing, immediately unites with the silicic acid (SiO_2) of the lining, with, perhaps, some minor lime or alumina in addition, to form a copious slag afloat upon the charge.

Owing to the large percentage of iron always present in the matte, as a chief source of fuel supply to insure requisite fluidity, the corrosion of the converter lining goes on apace, the whole of the free silica being quickly taken up so that the renewal of the lining becomes constantly requisite, at much delay and expense, after only a few hours' run. To avoid such frequent renewals of the acid lining, it has been proposed to employ a basic lining instead, this being generally composed of magnesite brick, as a material sufficiently refractory to protect the vessel shell and equally a non-conductor to prevent excessive loss of heat by radiation, at the outer surface of the converter. The silicious flux, for union with the iron oxid to form slag, was no longer derived from the lining, but, in the form of loose, pulverulent additions, was supplied at intervals, directly to the charge within the vessel. Experience soon showed that the converter with basic lining was nearly as short-lived as the earlier form which, as already noted, had been equipped with the corrodible acid lining. The twyers for the air blast were composed of perforated magnesite brick, the inner end of

each twyer being submerged during the blow, beneath the molten charge within the vessel.

As is well known, the entering blast chills the charge in near proximity to the air vents, so that a "cold nose" quickly forms and becomes adherent to the tip of the twyer. Constant vigilance on the part of the workman becomes requisite to dislodge the nose by thrusting his punching tool through the air channel of the twyer. Unless the nose be broken off, the twyer vent gradually closes and, by so much, the volume of entering air diminishes. The cold nose was especially adherent to twyers of magnesite brick and thus, in effort to clear the nose away, more or less of the brick itself chipped off, thereby disintegrating the body of the twyers at various points along the belt, and, so far, tending to loosen the compact structure of the brick lining throughout.

Our invention aims to correct the defects named and, to such end, we have devised a new method for bessemerizing copper matte in converters equipped with a non-corrodible lining, left free to shift under changing heat conditions, the plan being to deliver the requisite air blast at the molten bath in full volume, that is, without material leak loss in its passage through the converter lining, by which means the desired reactions are maintained in the bath while the lining is kept intact.

The invention further designs to provide a matte converter of improved sort for practice of the method, the vessel structure involving the presence at the outer shell of an inner non-corrodible lining, free to shift relatively thereto under varying heat conditions, in combination with a set of blast twyers extended through the lining and, at their receiving ends, established in continuous full delivery connection with the source of air supply.

In preferred practice the plan is to equip the converter with a non-corrodible lining of tenacious, coherent texture, left free to expand or shift under high heat, without risk of buckling or rupture, said lining to be united with a set of twyers projected through the converter shell, but flexibly sustained so as to participate in the play of the lining, up and down—in floating fashion, as it were—by which expedient each sepa-

rate twyer remains intact and neither suffers leaks to occur, nor presents an unyielding obstruction, as in former practice, most apt to start or dislodge the lining in its shift.

The invention further designs to form the flexible twyer of cast iron, extended entirely through the lining, but properly jointed at back to the air conduit in tight fashion to prevent all vagrant leaks of the blast, such as in prior usage tended constantly to undermine the coherent lining. Formed of metal, the improved twyer stoutly withstands the blows of the punching tool while, as experience shows, the "cold nose" that chills constantly at the twyer tip, is much less adherent than in the case of the earlier magnesia twyer; hence the nose detaches readily when attacked by the workman.

Referring to the drawings: Figure 1 is a side elevation view, the converter roof being shown in section; Fig. 2, a cross section, on line 2--2, Fig. 1. Fig. 3 is an enlarged sectional view on line 3--3 of Fig. 4, one of the improved tuyers being shown mounted in place through the lining with its outer end flexibly sustained at the converter shell. Fig. 4, a detail elevation at the twyer belt, with wind-box cover removed to display the mode for securing adjacent tuyers. Fig. 5, a detail cross section at line 5--5, Fig. 6, the mount for several adjacent tuyers being denoted by dotted lines. Fig. 6, a view in longitudinal section at the junction of the tuyers with the converter shell. Fig. 7, a sectional view of one of the separate tuyers at its union with the shell plate; and Fig. 8, an elevation of the twyer detached.

In familiar fashion, the converter has the usual cylindric body or shell 10 made of sheet steel and is equipped with ring flanges 11 resting upon trunnions 12 beneath, to support the vessel and allow for its easy axial turn, at such times as may be necessary during the progress of the blow. At one side, lengthwise of the converter, extends the wind-box 13, deriving its air supply by pipe 14 from some convenient source. The frame of the wind-box is riveted to the adjacent shell of the converter while, at its front, the box is equipped with a series of removable cover plates 15 to afford ready access to the box interior.

As shown at Figs. 1 and 2, the upper side of the converter shell is left open between ends, while a series of tie-rods 10^c extend across the opening to keep the shell from spreading, which otherwise might easily occur, once the inner lining expands or swells far enough under influence of the extreme heat.

Each twyer 16 consists of a hollow, iron casting, made square in cross section, to snugly adapt itself to the faces of the lining brick adjacent and extended entirely through

the lining for certain delivery of the air at the very tip end within. In position, the twyer is set at slight incline and is furnished with an enlarged head 17 that rests snugly within a square hole of retainer plate 18. Ordinarily, retainer plate 18 affords seat for a series of three tuyers next adjacent and is stoutly bolted to main shell 10 through its reinforce 19. A cross-tie 19, secured to the retainer plate, overlaps the outer ends of adjacent tuyers to help keep them in place.

About the neck and head of each twyer is a packing 17^a, generally of asbestos wicking, sufficient in quantity to stop the inflow of air from the wind-box to the lining next the shell and serving, besides, to sustain the tuyers, as by flexible air-tight joint, during rise and fall of the twyer at its free end, due to the "heave" of the lining, as the latter expands or contracts under changes of temperature, occurring within the converter.

Once the several tuyers are set in place, the operator proceeds to embed their outer ends, as well as the retainer plates and cross-ties adjacent, in a heavy coat of thick cement, which may be of plastic clay, although often composed of ground magnesite admixed with linseed oil, to the consistency of a stiff mortar. Under the heat of the converter, the coating referred to bakes hard and fast to parts adjacent, completely closing all vents and so far serving to check the flow of fugitive air currents from the wind-box, about the tuyers and past the shell into the converter lining beyond.

At the more exposed parts, the vessel interior is lined with magnesite brick 20 of usual sort but, instead of luting the layer of brick and tuyers adjacent by use of a cement of ground magnesite with slight addition of clay to render the cement sticky, the customary practice is to employ for the purpose, the same cement composition comprising ground magnesite with linseed oil admixed, ordinarily used for coating the inner face of the wind-box. Experience shows that the cement thus prepared bakes hard and fast to the brick and tuyers of the lining, and to the shell, completely closing all leak passages, otherwise most apt to develop, and remains tenacious and adherent at all extremes of temperature within the vessel. Apparently, the co-efficient of expansion for the particular cement is sufficiently close to that distinctive of the magnesite brick—and of the metal parts adjacent—to insure a practically air-tight lining which becomes essentially homogeneous throughout to prevent the circulation of leak air currents altogether.

In lieu of linseed oil, it is feasible to substitute core oil, such as the molders use, consisting of crude petroleum, with some minor percentage of rosin dissolved therein.

Obviously, any sort of cement having properties distinctive of the mixture of ground magnesite and linseed oil, chosen in usual practice, may serve the purpose, if the result be to insure the homogeneity of the lining, in the sense that no vagrant currents of air can circulate to accomplish disintegration. Except for matter of cost, the magnesite brick may be displaced and the lining be composed solely of the cement proper. But the baked bricks in compressed form better withstand the hard usage experienced in regular converter practice, and, for such reason are generally preferred. In ordinary use, the heat of conversion developed by the blast becomes intense enough to swell the inner lining which gradually expands, in turn, into the open space left at top of the converter shell, until, eventually, the lining comes in contact with the tie-rods 10°, oftentimes bulging them outwardly. Being of closed, arched form, the inner non-corrodible lining acts to sustain itself despite the expansion, and, by reason of the peculiar cement chosen, not only keeps air-tight joints and courses, but also at junction with the floating twy whole. The marked heave in place experienced by the lining, would constantly tend to break or bend the twy whole embedded therein, were it not that each twy whole is flexibly sustained at back, leaving the main body and tip end free to "float" with the lining in complete avoidance of all rupture or dislocation. That is to say, the lining proper and the twy whole united therewith maintain a tenacious, coherent relation, despite the shift, while the twy whole are kept tight outside both at converter shell and air conduit beyond, effectually preventing the familiar inroads on the lining, before met with, and thus preserving the life thereof for weeks or months at a time, during constant use.

Obviously, the details of structure can be varied according to the skill of the mechanician without departure from the essentials of the invention.

Having thus described the invention, what we claim as new, and desire to secure by Letters Patent, is:—

1. In copper matte converters, the combination with an outer shell, of an inner, non-corrodible lining left free to expand under high heat, and a set of blast twy whole embedded in such lining, but flexibly sustained with relation to the outer shell to participate in shift of the lining while still held in tight relation with the air supply, substantially as described.

2. In copper matte converters, the combination with an outer shell having an open top and a non-corrodible inner lining, arched over to freely expand adjacent such top, of the series of blast twy whole, flexibly sustained with relation to the outer shell and extended

through the lining to participate in the shift thereof while still preserving the tight, coherent state of such lining, substantially as described.

3. In copper matte converters, the combination with an outer shell, of the internal, non-corrodible lining free to heave therein, a set of blast twy whole embedded in and extended through said lining, and an external wind box within which such twy whole are flexibly sustained in air-tight state, substantially as described.

4. In copper matte converters, the combination with an outer shell, of the internal, non-corrodible lining free to heave under extreme heat, the blast twy whole extended through the lining but flexibly sustained adjacent the converter shell, a wind-box inclosing the inlets for said twy whole and a cement coating to close the junction of each twy whole with the converter shell and with the wind-box respectively.

5. In copper matte converters, the combination with an outer shell provided with an internal lining, of a series of metal twy whole, square in cross-section, sustained flexibly from the shell and embedded in the lining brick to form a snug joint therewith, substantially as described.

6. In copper matte converters, the combination with an outer shell, of a series of projecting metal twy whole, united loosely to the shell, the retainer plates to receive the twy whole heads, cross-ties to keep adjacent heads in place and an internal lining in which the free ends of the twy whole are embedded, substantially as described.

7. In copper matte converters, the combination with an outer shell, of an inner non-corrodible lining shiftable, relatively to the shell under the changing heat conditions, and a set of blast twy whole extended through the lining and having continuous full delivery connection at their receiving ends with the source of blast supply; substantially as described.

8. In the bessemerizing of copper matte in converters having a non-corrodible lining, the method of maintaining the desired reactions in the bath and preserving the lining intact as it expands and contracts under the changing heat conditions to which it is subjected, which method consists in conducting through the non-corrodible lining and delivering into the bath the air blast required for the blow and guarding it during transit through the lining against diminution of its volume and leakage into the body of the lining; substantially as described.

9. A converter for bessemerizing copper matte comprising an outer shell, an inner tenacious, coherent lining continuous with the shell and formed of magnesite brick, and blast twy whole embedded in the lining, the joints of the magnesite brick with one another

and with the twyers being luted with a cement formed of ground magnesite admixed with a suitable oil, substantially as described.

10. A converter for bessemerizing copper matte consisting of a cylindrical shell rotatably sustained in horizontal position and open at its upper side, cross tie-rods connecting the side edges of said opening, an inner, non-corrodible lining arched over at the top and free to expand within the shell, and

blast twyers embedded in the lining and having a continuous full delivery connection at their receiving ends with the air supply, substantially as described.
